F. M. SLOUGH,

LINE INTERCONNECTING SYSTEM
APPLICATION FILED JAN. 6, 1919.

1,437,367.

Patented Nov. 28, 1922.

UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

LINE INTERCONNECTING SYSTEM.

Application filed January 6, 1919. Serial No. 269,823.

To all whom it may concern:

Be it known that I, FRANK M. SLOUGH, a citizen of the United States, residing in Rochester, in the county of Monroe and 5 State of New York, have invented a certain new and useful Improvement in Line Interconnecting Systems, of which the following is a specification.

My invention relates to telephone exchange systems in general, but more particularly to so-called automatic telephone exchange systems in which the general operation of interconnecting calling and called lines is accomplished automatically under 10 the control of the calling subscriber.

Generally stated the object of my invention is the provision of an improved and highly efficient telephone exchange system.

Special objects of my invention are the provision of means whereby the resulting talking connection between two subscribers may be made through a minimum of switch contacts, so that the chances for trouble due to improper connections made through such 20 contacts may be reduced to a minimum; the provision of a novel arrangement whereby each subscriber provided with an individual line switch, may select a non-engaged trunk circuit, common to a group of such individual switches, and may thereafter by the operation of selecting apparatus, which may not be individual to such a selected trunk circuit, cause the operation of the line switch of the called subscriber to cause it to connect to the said connected trunk circuit; also the provision of means whereby after a trunk 30 circuit has been selected by a calling line, one of a plurality of directly controlled switching mechanisms may be selected by the calling subscriber, such a selected one being one that is not in use at the time, and the selected switching mechanism is thereafter directly operated under the control of a calling subscriber's substation apparatus to locate the line switch of the called line and cause it to seek and connect to the trunk circuit first selected by the calling 40 line.

Another object is the provision of means

whereby after the interconnecting function 50 having been performed, the directly switching mechanism may be discharged from the connection, and may be made available for the use of other calling subscribers.

To the foregoing and other useful ends, 55 I provide certain features of construction and novel arrangements which constitute a substantial contribution to the general art of telephony, particularly the art of automatic telephony, as will hereinafter more 60 fully appear.

In the accompanying drawing the figure shows two telephone lines LA and LB leading to substations A and B, from individual line switching apparatus LSA and LSB for 65 each of the lines. Other lines and line switching apparatuses will be, of course, provided in practice, only two of them being shown for the purpose of illustrating my invention.

At TK I show a series of circuit conductors interconnecting corresponding sets of passive contacts arranged for possible engagement by the wipers of each line switch. These circuit conductors TK comprise conductors of a trunk circuit of a group of trunk circuits, each trunk circuit of which will be similarly provided with passive contacts on each line switch of the group of line switches. Only the one trunk circuit however and the 80 associated passive contacts for two line switches being illustrated, it being understood, however, that other trunk circuits will be provided similar in character to the trunk circuit TK.

Associated with the trunk circuit TK, is shown controlling apparatus LK for the trunk circuit, this controlling apparatus consisting of relays, etc., and also an individual non-numerical switching mechanism 90 LKS with which each trunk circuit is provided. This non-numerical switching mechanism is enabled by its wipers 32, 33 and 34 to make connection with one or another of a plurality of switching mechanisms, such as the switching mechanism LSW as may be at the time in an idle or unused condition, such switching mechanism as LSW being

adapted to be directly operated under the control of a calling substation to connect its wipers, such as the wipers 38 and 39, to circuit conductors leading to the line switch mechanism, such as LSB of the called line.

Referring now to the substation apparatus A, I show a telephone substation comprising the usual transmitter, receiver and bell illustrated by the usual symbols and a hook switch 101, and the usual form of circuit interrupting dial DL. From this substation apparatus a telephone line LA extends by line conductors and line switch mechanism LSA. It is understood that this line and line switch are but one unitary telephone equipment individual to a particular telephone line, other like unitary equipments being provided for other telephone lines, such as the equipment consisting of the substation apparatus B, line conductors LB and line switch mechanism LSB. In this description the line having the substation A will be arbitrarily chosen as the calling telephone line, and the line having the substation B will be elected as the called telephone line.

The line switch mechanism for each of the lines is in general of a well known form, in which a set of line switch wipers, such as the wipers 22, 23, 24, 25 and 26 of the line switch LSA, normally rest upon a set of contacts belonging to one of a plurality of selectable trunk circuits, which trunk circuit was the last employed by the line switch in establishing the last established connection. Other sets of contacts for other trunk circuits lie in the path of the line switch wipers and are adapted to be successively engaged by the line switch wipers when the line switch is operated under the propelling influence of the line stepping magnet LSM.

Associated with each of the line switches are a plurality of relays consisting of a line relay L and line cut-off relay CO, and a switching relay SWR, the first two of which control the actuation of the stepping magnet LSM, and control the extension of the line and local circuit controlling conductors to the line switch wipers. The relay SWR is adapted to be operated when the line with which the line switch is associated is a called line, and in which case it switches certain connections as will be later described, in order to make the line switch mechanism perform its trunk hunting operation under a different kind of control from that exercised by it when the line with which it is associated is a calling line.

Associated with each line switch, such as the line switch LSA, are a plurality of sets of passive contacts, one set being provided for each trunk circuit with which connection may be made by the line switch. Two of these sets of contacts are illustrated in

the drawing one for each of the illustrated line switches, but one of them however, that one consisting of contacts 27, 28, 29, 30 and 31 for the line switch LSA being shown as connected to the circuit conductors, as TK, of a trunk circuit; it will be understood though that each set of contacts with which the line switch is provided, of which there may be 10 or more sets, will be likewise connected to a similar set of circuit conductors, through which circuit conductors telephonic interconnecting and switch controlling circuits may be associated between calling and called lines through the intermediary control of trunk controlling mechanism, such as LK of the trunk circuit TK.

With the switching relay SWR of a given line switch, such as the line switch LSA in its normal or unoperated position, which is the position which is assumed when the associated line is a calling line, throughout the ensuing connection, only the line switch wipers 22, 23 and 26 are connected to the circuits of the line switch, the other wipers 24 and 25 being operatively disconnected therefrom, and during such a connection are unused. It is only when the line is a called line and the relay SWR of the called line switch is operated, that these wipers are used and are operatively connected to the line switch circuits to perform functions in connection therewith later to be described. In passing it may be said that such line switch wipers corresponding to the wipers 24 and 25 of the line switch LSA for the line switch LSB, are shown at 4 and 5.

When a call is initiated over a calling line, such as the line LA, a connection is thereafter automatically made to an idle trunk circuit, such as the trunk circuit TK by means of the line switch, such as LSA, certain apparatus LK of the selected trunk circuit TK, is thereupon placed under the control of the calling subscriber, and under this control an individual switch mechanism LKS for the selected trunk circuit TK, is thereupon operated to extend controlling circuit conductors of the trunk circuit TK to circuit conductors of an idle or unused numerical switch mechanism diagrammatically illustrated at LSW. This numerical switch mechanism may be of any of the well known forms, but in this description it will be, for convenience, considered to be of the form well known in this art, which consists of a switch brush carriage adapted under the successive control of successive series of impulses to cause switch wipers attached to this carriage to be conveyed first, under the control of the first series of impulses in a vertical direction to select a group of contact sets, and then to be conveyed in a horizontal direction to select of the group a contact set which is connected to circuit conductors leading to the called line apparatus. In the

embodiment illustrated I only require a single pair of switch wipers to be moved into contact with contacts of the called line, this making for simplicity of design of the 5 switching mechanism.

Associated with the switch mechanism LSW, I preferably provide the usual forms of controlling means, consisting of a primary stepping magnet PM for propelling 10 the wipers, for instance, in a vertical direction, and a secondary stepping magnet SM for propelling the wipers in a secondary direction, a release magnet RM to restore the switch mechanism LSW to normal after the 15 period of use after the same has expired, and a busy test relay BT by means of which the switching apparatus LSW is adapted to make a busy test of the called line terminals.

20 Control relays as will be later described in detail, such as the impulse relay IR, the subsidiary slow releasing relay RR, other subsidiary slow releasing relays D and KL and relays Y, Z and X are provided for 25 purposes hereinafter set forth. Common control means for a plurality of such switching mechanisms, as the mechanism LSW are provided consisting of the restoring switch RSW adapted to contact with passive contacts, such as the passive contact 102 associated with the switching mechanism LSW, for each of the associated switching mechanisms of the group and a stepping magnet F for the said restoring switch, together 30 with a relay E, controlling the same. This common controlling means is provided for the purpose of preventing more than one called line switch selected by the numerical switching mechanism LSW from operating 35 at a time, so that on simultaneous calls being made to a plurality of such numerical switching mechanisms, within an interval following such a call, only one called line switch may, as such, operate at a time insuring that connection will be made to the 40 proper line desired.

Having now described the instrumentalities employed in the illustrated embodiment of my invention, I will now describe the 45 operation of the same in detail, reference being made to the drawing in which as above stated, election is made of the line having the substation A as the calling line, and the line having substation B as the 50 called line.

Assume that the subscriber A initiates the call by taking his receiver from the hook and closing the hook switch contacts 101, a circuit being therefore closed through normal contacts 102 and 103 of the cut off relay CO, to a slow releasing line relay L, the common source of current BTY being included in this circuit to cause the operation of the line relay L, which being operated 55 will attract its armatures closing contacts,

104 and 105, the adjustment of these contacts being preferably such that the contact 104 will be definitely closed prior to the closure of the contact 105. At this time the line switch wipers 22, 23, 24, 25 and 26 had 70

been resting upon a set of trunk circuit contacts as illustrated, and it is to be assumed in this description that this set of contacts is connected to circuit conductors leading to a busy or used interconnecting trunk line, 75 and that therefore because of the busy condition of such a trunk line, the contact upon which the wiper 26 at the time rests, is connected to the ground pole of the common source of current BTY, and that therefore a 80 circuit is closed including the winding of the stepping magnet LSM of the line switch including the common source of current, this circuit being traced as follow: from the ground pole of battery, through the common source of current, the winding of the stepping magnet LSM, normally closed contacts 106 carried by its armature, now closed contacts 104 of the line relay L, normally 85 closed contacts 107 of the relay CO, normally closed contacts 108 of the switching relay SWR, and from thence through the wiper 26 to ground, which we have described as connected to the passive contact upon which this wiper 26 rests. This circuit being 90 closed, the stepping magnet LSM will be thereupon actuated, and because of the contacts 106 carried by its armature being thereupon broken, will again immediately 95 retract its armature, the mechanical connection between the armature and the wiper carrying member being preferably such that the same is advanced upon the retraction of the armature, the arrangement in this respect being like that illustrated in the application of Bert G. Dunham, S. No. 227,462, filed Oct. 6, 1904. Therefore, the switch wipers of the line switch will be advanced 100 from the passive set of contacts upon which they have been resting, to the next succeeding set of passive contacts consisting of the contacts 27, 28, 29, 30 and 31 associated with the trunk circuit TK. The wiper 26 will be so constructed that at no time will it

105 pass out of contact with all of the contacts in its path, that is, it will be provided with a broad enough wiping surface so that in passing from a contact of one set to the corresponding contact of the next set of contacts, it will make contact with the second 110 contact prior to the breaking of the contact with the first contact; thus as long as the wiper 26 engages both trunk lines whose contacts adapted to be engaged by the wiper 26 are therefore connected to ground, the 115 circuit for the stepping magnet LSM will be continuous, and the stepping will continue until such condition is over by the final carrying of the wiper 26 into contact with a 120 passive contact such as the passive con-

125 130

tact 31 of the trunk circuit TK, which contact is not connected to ground, signifying that the associated trunk circuit is in an idle or unused condition. Under such a condition, the low resistance connection to ground which has previously been existing through the contact wiper 26, is removed and a high resistance connection only to ground remains, this comprising the winding of the cut off relay CO and now closed contacts 105 of the line relay L.

The winding CO being traversed by current on account of its inclusion in the energizing circuit of the stepping magnet LSM, which circuit includes the source BTY will attract its armatures. In the meantime, however, the stepping magnet LSM will cease the intermittent operation of its armature, since the resistance of the winding CO is too high to permit enough current to pass through it to operate the magnet LSM. The armatures of CO being attracted, the line relay magnet L will have its circuit opened at the contacts 103 which are now broken, and will being slow releasing slowly restore its contacts 104 and 105 to their normal open condition.

During the period of deenergization of the line relay L, the lower armature of the relay CO passed from its normal position wherein it maintained the contacts 107 closed, to its operated position, wherein contacts 107 are opened and its front contacts are closed, the energizing circuit maintaining the relay CO operative after the line relay releases its armatures being traced as follows: from the ground pole of the source BTY, the said source, the winding of the stepping magnet LSM, normal contacts 106 thereof, the winding of the relay CO, now closed contacts 109 thereof, normal contacts 108 of the relay SWR, switch wiper 26 and passive contact 31 engaged thereby, and now closed contacts 110 of slow releasing relay LSR associated with the trunk circuit, this relay having been previously operated prior to the release by the line relay L of its armatures.

The circuits involved in the operation of the relay LSR will now be traced: when the line switch wipers 22, 23, 24, 25 and 26 made connection with the set of contacts 27, 28, 29, 30 and 31 of the trunk circuit TK, and after the relay CO was operated as above described, the line conductors LA of the line having the substation A would extend through now closed contacts 111 and 112 to switch wipers 22 and 23, and by interconnection of these wipers with the passive contacts 27 and 28 of the selected trunk line, the line conductors would extend to the trunk controlling apparatus LK, where a bridge of these conductors consisting of the impedance coil ZZ and the relay SR, together with the included common source of current BTY was made.

Current from the source flowing through the relay SR will cause it to be energized, attracting its armature and closing contacts 113 in the circuit of the slow releasing relay LSR, which circuit likewise includes the common source of current BTY. Thereupon the relay LSR is energized attracting its armatures, closing the contacts 110 before mentioned as now included in circuit with the winding of the relay CO of the connected line circuit, and the contacts 114 are closed in the circuit of the busy tone generator BZ, which busy tone generator thereupon begins to project busy tone current over the calling line conductors, the circuit for the projection of the same leading to the passive contact 27, through normal contacts 115 of a tandem wound slow releasing relay RL, the now closed contacts 114 of the relay LSR, and normal contacts 116 of the relay 117. This busy tone current will persist until after the dialing operation by the subscriber has been completed, and will be discontinued in that case only if the called for line is found to be idle, or under such other conditions as will later appear.

Other means of controlling the busy tone circuit might be provided in place of that herein specifically set forth, the particular method of control therefore which is herein illustrated and described, being chosen because of its simplicity and lack of complications insuring positive and unvarying operations of like nature under similar conditions.

Upon the relay SR being energized, a circuit is likewise closed for the individual switch line relay LMR of the individual switch which is associated with the trunk circuit TK selected, this circuit being traced from the ground pole of battery, through contacts 113 of the relay SR, normal contacts 118 of the relay RL, normal contacts 119 of the individual switch cut-off relay COM, the winding of the line relay LMR, which is made slow releasing in a like manner and for a similar purpose as was done in the case of the line relay L for the line switch LSA, the circuit being continued to the common source of current BTY to the ground pole of battery thereof. The closure of this circuit at the contacts 113 will cause the energization of the relay LMR and which retracting its armatures, will close successively the contacts 120 and 121, the successive closure being secured by proper adjustments to cause the individual switch mechanism to operate, to make connection with an idle or unused numerical switch mechanism, such as the numerical switch mechanism LSW whose incoming conductors NSC terminate in passive contact sets, such as the contact set comprising contacts 122, 35, 36 and 37, in each individual switch for each trunk circuit of the group of trunk circuits employed. The individual switch mechanism LKS, except for

the absence of the switching relay SWR is structurally very much like the line switch mechanism LSA, individual to the different lines, certain differences being of course required by different conditions under which the individual switch mechanism LKS must operate.

The active switch wipers 123, 32, 33 and 34 normally rest upon the passive contacts 10 which although, not so shown, would be connected by conductors like the conductors NSC to the numerical switching mechanism of the same group as, and like unto the numerical switching mechanism LSW. Should 15 such a numerical switching mechanism be at the time engaged, the passive contact upon which the wiper 34 normally rests will be connected to ground in a manner which will be made more apparent in the description 20 which follows for the switching mechanism LSW.

Sufficient for the present, however, is it to say that the presence of this ground denotes a busy switching mechanism and 25 causes the non-numerical switch LKS to advance its wipers into engagement with the next set of contacts, and this action may be repeated if the next set of contacts is associated with a busy numerical switching 30 mechanism until a set of idle contacts, such as the set comprising the contacts 122, 35, 36 and 37 is reached, whereupon there will be found no ground connection to the contact 37 at the time engaged by the switch wiper 34, and that therefore the current through 35 the stepping magnet MSM for the switch LKS will be cut off, and the cut-off relay COM will be energized in exactly the same way as was the case as before described for 40 the switch LSA, reference in that case having in this description been made to the similar functioning stepping magnet LSM and the similar cut-off relay CO, so that for brevity this operation will not be re-described in detail.

Sufficient to say at this time, that when the contacts of an idle switch mechanism as LSW are reached, the wipers will be stepped in engagement with these contacts, 50 the cut-off relay COM energized being held energized over a circuit comprising in part the wiper 34, passive contact 37, the normally open or now closed contacts 124 of the slow releasing relay RR which for this 55 function corresponds to the slow releasing relay LSR, which relay RR is held operated by normally open but now closed contacts 125 of a relay IR which corresponds, for this function, to the relay SR, the operation 60 of the relays LSR and SR in connection with the switch LSA having previously been described. The relay IR now operates over a circuit including the active switch wiper 33 and the passive contact 36 65 of the switch IKS, and through normally

open but now closed contacts 113 of the relay SR; so that it is under the control of the relay SR, being operated when the relay SR is operated and released when the relay SR may be released. The relay SR 70 being at all times under the control of the subscriber at the calling substation A, the relay IR is likewise under this control, the action of the subscriber's dial DL and switchhook contacts 101 upon the relay SR 75 being repeated by the relay SR in its control over the relay IR during the period through which the switching mechanism LSW, with which the relay IR is associated, remains in association with this connection. 80 The relays IR and RR are a pair of "fast and slow" relays which operate in a well known manner under the control of the calling subscriber's dial, as DL, to cause the successive operation of primary and secondary stepping magnets for the switching mechanism LSW. This operation will now be described.

The subscriber first operates his dial to interrupt the circuit of the relay IR a certain number of times, and IR will thereupon retract its armature a certain number of times, depending upon the first digit of the called line number.

The contacts 125 will thereupon be opened 95 for very short periods during these interruptions, but such openings as will thereby be introduced in the circuit of the slow releasing relay RR, will not cause the relay 100 RR to retract its armatures. Consequently 105 upon each closure of the normal contacts 126, a circuit will be completed for the primary stepping magnet PM, this circuit including the slow releasing relay D, which will keep its armature attracted during the 110 series of circuit interruptions, and for a brief period thereafter for a purpose which will be described, but which will be well understood by those versed in this art when it is explained that the relay D controls the 115 escape magnet Y for the side switch having wipers 44, 45, 46 and 47, and that this escape magnet Y advances these side switch wipers upon each deenergization. During the first 120 series of circuit interruptions, the side switch wipers are in first position, as shown. The primary stepping magnet PM having its circuit closed at the contacts 126 a definite number of times, will step the switch carriage carrying the wipers 38 and 39 in a 125 primary direction a corresponding number of steps to locate the group in which the passive contacts 40 and 41 of the called line are located.

In passing it will be understood that the 125 passive contacts for each line are multiply connected in the different numerical switching mechanisms of the system, of which the switch mechanism LSW is one. This is also true of the passive contacts, such as 122, 35, 130

36 and 37 which are multiply connected to other like passive contact sets for the other individual switches IKS of the other trunk circuits of the system, this in a manner like 5 that illustrated for the trunk circuit TK, which has, as illustrated, multiply connected passive contact sets for the telephone line switches, such as the line switch LSA and the line switch LSB. This system of multiply connected contact sets for different 10 switches is well known in the art and will not therefore be described in all its aspects.

At the end of the first series of circuit 15 interruptions, the contacts 126 being thereupon opened for a definite, relatively long interval, current in the circuit of the slow releasing relay D being thereby interrupted for a sufficient interval to allow it to retract its armature; and the slow releasing 20 relay KL which has been held operated by the closure of the contacts 48 of the slow releasing relay D, will soon after retract its armature, opening the contacts 49 in the circuit of the escape magnet Y, which 25 magnet has been kept energized by the closure of these contacts 49; and the escape magnet Y now being deenergized by the opening of these contacts, the side switch wipers 44, 45, 46 and 47 will advance to 30 their second operative position. In the second position various circuit changes are effected as will now be described.

Previously, however, certain sets of contacts known as off normal contacts and illustrated in the drawings at various places and marked with the reference characters ON, have been operated, this operation being accomplished in the well known manner upon the first movement of the switch carriage under the control of the first impulse of the first series of circuit interruptions. The effect of the operation of one of these ON contact sets is to close the contacts 50 insuring that a connection to 45 ground is maintained on the passive contact 37 of the switch LKS, to maintain the cut-off relay thereof, COM, operated until the final later restoration of the switch LSW to normal, whereupon these contacts 50 will be opened as will be later noted.

The subscriber will now again operate his dial to produce a second series, containing a certain definite number of circuit interruptions to step the numerical switch wipers 55 38 and 39 in a secondary direction to locate the terminals 40 and 41 associated with the called line desired. This stepping is accomplished by the intermittent operation of the contacts 126 in the circuit of the secondary stepping magnet SM, which circuit as in the case of the stepping magnet PM 60 contains the slow releasing relay D which relay is maintained energized during this second series of circuit interruptions and 65 caused to release its armature shortly after

the circuit interruptions have ceased. The circuit above mentioned is traced as follows: from the ground pole of battery, through the contacts 126 of the relay IR, through the now closed contacts 51 of the slow releasing relay RR, the winding of the slow releasing relay D, normal contacts 52 of the relay X, normal contacts 53 of the busy test relay BT, the winding of the secondary stepping magnet SM, second position passive contacts and side switch wiper 46 to the negative pole of the source of current and through the said source BTY, to the ground pole of battery. Current from the said source besides keeping the slow releasing relays D and the controlled slow releasing relay KL continuously operated, will cause the escape magnet Y controlled by the relay KL to be energized by the closure of the contacts 49 of the relay KL, and will 70 also intermittently operate the secondary stepping magnet SM a definite predetermined number of times according to the 75 number of circuit interruptions of the second series to cause the stepping of the switch wipers 38 and 39 to contact with the passive contacts 40 and 41 of the called line.

The relay X will not be operated at this time regardless of the condition of operation of the relay Z, which for the present 95 we will assume is in normal un-operated condition, since the closure of the contacts 54 of the escape magnet Y and the circuit thereby extending through the second position passive contacts and side switch wiper 100 47 through the winding of the relay X, and from thence to normal contacts 55 of the relay Z to ground, will be shunted by the prevailing direct connection to ground through the contacts 49 of the relay KL. However, 105 at the end of this second series of impulses and the contacts 126 being definitely opened for a given length of time, the relay D will retire its armature, opening the contacts 48 in the circuit of the slow releasing relay KL, 110 which, retiring its armature, will open the direct connection to ground through the contacts 49, removing the shunt hitherto established about the winding of the relay X; and the relay X, assuming the continued 115 non-operation of the relay Z, will be operated in series with the winding of the escape magnet Y, preventing the de-energization of the escape magnet Y for the time being, or until the circuit in which the winding of the escape magnet Y and the winding of the relay X is later opened upon the subsequent operation of the relay Z. The relay X being operated completes a circuit 120 for the relay 117 controlling the busy test circuit, by the closure of the contacts 100 of the relay X; this causes the relay 117 to be operated, the circuit therefore including normally open contacts 151 of the relay COM, wiper 123 and passive contact 122 of the 125 130

- switch LKS, the said contacts 100 and the source of current BTY which energizes the relay 117, causing it to open contacts 116 in the circuit of the busy tone current source 5 BZ, so that during the period prior to the control of the called line switch by the switching mechanism LSW, the busy tone current will not be projected to the calling subscriber, if the called line is not busy.
- 10 Now the switch having the wiper RSW is shown as a rotary switch with a wiper traversing, as illustrated, five passive contacts in succession, it being taken for granted for the purpose of description that the rotation is in a clock-wise direction. Each of these passive contacts, such as the passive contact 102 is associated with a different numerical switching mechanism, such as the switching mechanism LSW for the contact 15 102, and whenever the side switch wiper RSW is at rest upon one of these contacts, the associated numerical switching mechanism may exercise a control over one of the line switches of the system, which line switch 20 is one belonging to the line called by the calling subscriber who at the time has control over the particular associated numerical switching mechanism. Thus only one of the switching mechanisms of the group 25 containing the switching mechanism LSW may operate a called line individual switch at the same time. This is to prevent wrong connections being secured by calling subscribers, and other difficulties which might 30 ensue were this not the case.
- If the switching mechanism RSW does not rest upon the contact 102 of the switching mechanism LSW, when as in this description the time has come for the switching 35 mechanism LSW to exercise its control over the called line switch, then, if another switching mechanism is not at the time exercising such control, by the operation of the relay X as previously described, the 40 switching mechanism LSW may cause the wiper RSW to advance step by step under the propelling influence of the stepping magnet F to the position wherein it contacts with the contact point 102 of the numerical 45 switching mechanism LSW, whereupon the step-by-step motion will cease. The stepping magnet F under such a condition is actuated over a circuit traced as follows: from the ground pole of battery, through 50 normal contacts 56 of the relay Z, the normally open or now closed contacts 57 of the relay X, the normal contacts 58 of the common controlling cut-off relay E, and from thence through normal contacts 55 mounted on the armature of the stepping magnet F, through the winding of the said stepping magnet, through the source of current BTY, to the ground pole of battery. The stepping magnet thus will be intermittently operated under the controlling in-
- fluence of its intermittently broken contacts 59, until the wiper RSW coming into contact with the contact 102, will close a circuit for the relay Z, in which circuit the common controlling cut-off relay E is also included to 70 operate the relays Z and E the circuit being traced as follows: from the ground pole of battery, through now closed CN contacts, the winding of the relay Z, passive contacts 102 and switch wiper RSW, the winding of the relay E, through the source of current BTY to the ground pole of battery.
- The relay E having operated, will break the circuit of the stepping magnet at 58, which circuit will also be interrupted by 80 the operation of the relay Z at the contacts 56. The contacts 55 of the relay Z also being broken, will interrupt the circuit of the relay X, and the escape magnet Y will also be restored to normal, the escape 85 magnet Y allowing the side switch wipers to pass into third position. This is the position in which the called line switch is operated under the control of the numerical switch LSW, and in describing the operation of the system up to this point, it has been assumed that the called line was in a free or idle condition, and that therefore connection might be made with the same by the calling line. However, if this was 90 not the case, the side switch wipers would be prevented from advancing into third position, as will now be described.
- Under the assumption that the called line was busy at the time that the side 100 switch wipers were in second position and after the end of the second series of circuit interruptions to select the called line, a circuit would have been closed for the busy test relay BT and the slow releasing relay 105 KL, as soon as the slow releasing relay D had retracted its armature again restoring its normal contacts 60. This circuit may be traced as follows: from the ground pole of battery, through the source BTY, the winding of the slow releasing relay KL, the normal contacts 60 of the slow releasing relay D, the winding of the busy test relay BT, normal contacts 61 of its set of make before 110 break contacts, second position contacts and 115 side switch wiper 45, numerical switch wiper 39, the passive contact 41 of the called line, and from thence to ground which will be placed upon the conductor leading to the contact 41 whenever the cut-off relay CO of the 120 called line is energized, as has been described, and line relay L is energized, ground in this case being placed on the conductor leading to the contact 41 from the normally open contacts 62 of the line 125 relay L. Therefore, on busy line condition current flowing over this circuit would energize the busy test relay BT, and the slow releasing relay KL and these relays would attract their armatures, the armature for 130

the relay BT closing locking contacts 63, and causing the subsequent opening of the contacts 61, the latter to open the test circuit leading to the brush 39. The locking contact 63 being closed, a locking circuit for the relays BT and KL will be completed therethrough, traced as follows: from the ground pole of battery, through the now closed off normal contacts ON, through the contacts 63 and the winding of the relay BT, through normal contacts 60 of the relay D, through the winding of the slow releasing relay KL, through the source of current BTY to ground.

15 The contacts 49 of the relay KL being closed, will maintain the escape magnet Y energized and the off normal contacts ON will maintain this condition continuous until the restoral of the switching mechanism 20 LSW to normal. In the meantime the subscriber having completed the dialing operation, will place the receiver on his ear, and the line being busy nothing will occur to remove the busy tone current from the busy 25 tone source BZ from the line the application of such source having as described previously occurred, the characteristic busy tone sound will be heard in the receiver and the subscriber will know that the called 30 line is busy, therefore not accessible for a connection and will therefore retire his substation instrument, opening the contacts 101 of his switchhook at the substation A.

The opening of the switchhook 101 will 35 automatically restore the central office mechanism to normal. First the relay SR in the substation line circuit will be restored, opening the contacts 113 in the circuit of the relay LSR of the trunk circuit 40 controlling apparatus LK retiring this relay and in the circuit of the impulse relay IR of the switching mechanism LSW, which relay will also be retired. The relay IR being retired, will retire the relay 45 RR and a circuit will be completed for the release magnet of the switching mechanism LSW including normal contacts 126 of the relay IR, normal contacts 64 of the relay RR, off normal contacts ON and winding of 50 release magnet RM, through the source of current BTY to ground. Current from the said source will energize the release magnet to restore the switching mechanism LSW, a locking circuit for the release magnet being closed through contacts 65 and the off normal contacts ON to insure that the release function will continue until the switch is entirely restored to normal. After this has 55 occurred, the ground at the off normal contacts 50 and the normally opened contacts 124 of the relay RR being removed from the conductor leading to the passive contact 37 of the individual trunk switch LKS, the trunk switch LKS will be restored to normal 60 by the subsequent retiring of the cut off

relay COM opening all of its contacts. The wipers of the trunk switch will remain quiescent as the individual switch illustrated and described is of that type wherein the wipers do not return to any special position 70 after each connection, being merely operatively dissociated from the controlling circuits by the opening of relay contacts at the end of the connection. Such a switch is shown in the application of C. C. Bradbury, 75 Serial No. 561,766, filed May 16, 1910, reference to which may be had for the purpose of securing a better understanding of such a switch than this brief description thereof affords.

80 The relay LSR of the trunk controlling apparatus LK having been retired as previously described, the ground connection to the passive contacts 31 of the calling line switch LSA will be removed by the opening 85 of the relay contacts 110 of the relay LSR, thus restoring the cut-off relay CO of the line switch LSA, which restores the apparatus of this line switch mechanism to its normal position. All of the apparatus involved in the attempt to make connection with the called line has now been restored 90 to normal.

To resume the narrative of the connection, at the point where the same was broken off, 95 to describe the operation of the circuits in case the line was found to be busy, we will now continue the narrative making the assumption that the line called for was not busy but idle, and therefore available for a 100 connection. The narrative is resumed at that point wherein the side switch wipers 44, 45, 46 and 47 had advanced into third position.

105 Side switch wiper 46 being in third position will connect battery in the circuit of the relay CR, through passive contact 35 and active wiper 32 of the individual switch LKS, normally open contacts 66 of the relay COM, winding of relay CR, through normally made contacts 118 of the relay RL and normally open contacts 113 of the subscriber controlled relay SR. The slow releasing relay CR will thereupon be energized, one effect of the energization being as 115 follows; the normally open contacts 67 will be closed completing a circuit including battery the resistance coil 68 for the relay RA and the normally open contacts 70 of the relay SR which being energized will attract 120 its armatures. The closure of the contacts 69 thereby completes a locking circuit for the relay RA likewise including battery, the resistance coil 68 and the normally open contacts 70 of the subscriber control relay SR. The relay RA will therefore for the present 125 be held actuated by virtue of this locking circuit.

130 The relay CR being operated will also open the contacts 71 and close the contacts

72, first removing the normal direct ground connection to the test conductor 73 of the trunk circuit TK and the second substituting therefore a relatively high resistance 5 ground connection including the winding of the relay RL. Thus instead of a direct ground being placed upon the passive contacts 10 associated with the trunk TK on the called line switch LSB, a resistance ground 10 connection will be substituted. All other trunk circuits of the group in which is located the trunk TK at this time will have a normal direct ground connection on their conductors, corresponding to the conductor 15 73 extending to passive contacts of all line switches of the group corresponding to the passive contact 10 of the line switch LSB. The busy tone circuit extending from the busy tone generator BZ through normal 20 contacts 116 of relay 117, normally open contacts 114 of the relay LSR and normal contacts 115 of the relay RL to the trunk line talking conductor leading to the passive contact 27 of the calling line switch and 25 from thence to the calling line, will have been interrupted by the opening of the contacts 115 when the relay RL was operated, which as has been described, occurred immediately following the movement of the 30 side switch wipers into third position.

The side switch wiper 44 passing into third position, will extend a direct ground connection to a terminal of the relay SWR of the called line switch LSB, through active 35 switch wiper 38 of the switching mechanism LSW and passive contact 40 of the called line located therein, this circuit being traced through the winding of the relay SWR includes the source of current BTY and being 40 closed, causes the energization of the relay SWR, which being energized attracts its armatures switching circuit as follows: First the lower armature being attracted breaks the contact 74 in the circuit of the active 45 switch wiper 6, which when the line with which it is associated is a calling line, is known as the test wiper, and the closure of the contacts 75 substitutes the active switch wiper 5 as the test wiper in place 50 of the test wiper 6, the test wiper 5 being in operation when the line is a called line, and the test wiper 6 being in operation when the line is a calling line. Likewise the line wiper 4, when the contacts 76 are closed and 55 the contacts 77 are opened, is substituted for the line wiper 3, the line wiper 4 being used when the line is a called line and the line wiper 3 being used when the line is a calling line. 60 The contacts 78 being closed will complete a circuit for the line relay L, this circuit being traced from ground through the contacts 78, now closed, the normal contacts 79 of the relay CO, through the winding 65 of the slow releasing line relay L, and the

source of current BTY to ground. The line relay L being caused to operate, will close its contacts 180 and 62 successively, just as did the line relay L of the line LA 70 close its contacts 104 and 105, as has been previously described when the line LA was initiating the call. The closure of the contacts 180 will complete a circuit for the stepping magnet LSM, the circuit being traced as follows: from the ground pole of battery, 75 the winding of the stepping magnet LSM, normal contacts 81 thereof, the now closed contacts 80 of the relay L, normal contacts 82 of the relay SWR, called line test wiper 5, 80 and from thence to whichever of the passive contacts corresponding to the passive contacts 10 of the trunk circuit TK, as may be in contact with the test wiper 5 at the moment this circuit is closed, the circuit being continued from such an assumed test contact 10 of an assumed other trunk circuit, corresponding in structure to the trunk circuit TK, with which the assumed passive contact 10 is associated, through normal contacts 71 of a relay, such as CR, to ground. All trunk circuits except the trunk circuit TK will maintain through such contacts, as the contacts 71, a normal ground connection to its passive contacts 10, so that the circuit 90 for the stepping magnet LSM will be completed to ground whenever and during the time that the wiper 5 rests upon one of such other test contacts. This causes the stepping magnet LSM, intermittently operated 100 under the control of its own normal contacts 81, to step its associated set of wipers 2, 3, 4, 5 and 6 from trunk circuit, to trunk circuit passive contacts until the wiper 5 comes into contact with the test contact 10 105 of the trunk circuit TK used in building up this connection, and when this occurs there being no direct connection from ground to this passive contact 10, but only a connection through a resistance coil consisting of 110 a winding of the relay RL, sufficient current will not flow over this circuit through the said winding and through the winding of the stepping magnet LSM to operatively energize it, consequently the stepping magnet 115 will cease the stepping of the wipers and will remain quiescent with its associated wipers resting in contact with the set of contacts in which is contained the contact 10, which set is that one associated with the 120 trunk circuit TK. The relay RL will be operated and operatively locked, the locking circuit including the source of current BTY, the winding 83, now closed normally open contact 84 of the relay RL, and normally open contacts 113 of the relay SR, now closed. The relay CO of the line switch LSB, will at the same time be operated just as was the line switch relay CO of the 125 switch LSA, which operation has been de- 130

scribed, and which will not now be repeated. In like manner the slow releasing relay L will be retired as was the case with the corresponding relay of the calling line circuit, 5 and the line conductors LB will be extended by the closure of contacts 85 and 86 of the relay CO to the line switch wipers 2 and 4, and thence through the passive contacts 7 and 9 of the trunk circuit TK, to the line 10 conductors 87 and 88 of the interlinking controlling circuit LK of the trunk circuit TK.

The contact 79 of the relay CO will be broken, opening the circuit of the line relay 15 L and the contacts 89 will be closed, maintaining the relay SWR in operation independent of the connection through the side switch wiper 44 and third position contact therefor.

20 The relay RL being operated will cause the release of the individual switch LKS of switching mechanism LSW all of which will now be restored to normal. This is primarily caused by the opening of the contacts 118 in the circuit of the relays IR and CR. The relay IR is therefore deenergized retiring its armature, likewise causing the retiring of the relay RR, and a circuit for the releasing magnet which has been previously described, is completed through normal contacts 126 and 64 of the relays IR and RR respectively. The said release magnet RM being energized, causes the switching mechanism LSW to be restored to its 30 normal position of rest, and the above having occurred, ground connection will be removed from the passive contact 37 of the individual switch LKS, which ground connection through contacts 90 has hitherto 35 maintained the cut-off relay COM operative which will now retire its armatures, thus restoring the circuits of the individual switch LKS to normal.

The relay RL being operated, also opens 45 its contacts 152 and closes contacts 153. This is accomplished prior to the opening of the contact 72, subsequent to the opening of the circuit of the relay CR, which is slow releasing, so that there will be no actual rupture, and the circuit of the circuit 50 conductor 155 will subsequently be maintained continuous through now closed contacts 153 of the relay RL, now closed contacts 154 of the relay SR, to the ground 55 pole of battery, thus replacing the resistance connection to ground, through the winding of RL with a direct connection to ground, through contacts of relays mentioned RL and SR; this to isolate the trunk 60 circuit TK to subsequently operating called line switches involved in other connections. At this time the relays SR, RA, LSR and RL in the controlling circuits LK of the 65 trunk circuit TK are all operated, and in consequence a circuit is completed for the

sending of interrupted ringing generator, through a winding of the trip relay TR to the called line bell B, this circuit being traced as follows: from the ground pole of battery, through the source of battery BTY, 70 the ringing generator G, the interrupter I, the resistance lamp 91, the winding of the ringing trip relay TR, now closed contacts 92 of the relay RL, now closed contacts 93 of the ringing relay RA, passive contact 9 75 of the called line switch LSB, active wiper 4 in connection therewith, now closed contact 76 of the switching relay SWR, now closed contact 86 of the relay CO, one of the line conductors of the line LB, through the 80 signal bell Z, associated condenser and normal switchhook contacts and dial contacts of the substation B, the other line conductor, now closed contact 85 of the relay CO, active switch wiper 2 and passive switch 85 contact 7, line conductor 87 of the trunk circuit TK, and from thence through the resistance coil 94 and now closed contacts 95 of the relay RA to ground. The interrupter I alternately includes the generator 90 G, or the resistance coil 96 in this circuit to produce ringing or silent periods.

The subscriber at the station B responding to the ringing of his bell, will remove his receiver from the hook completing an 95 operative circuit for the flow of direct current from the source BTY, current from which source will be superposed upon the ringing current during the ringing period, and will cause the operation of the ringing 100 trip relay TR, which is so adjusted and constructed to be only operative to the flow of direct current to continuously close its contacts 97. These contacts being closed, will short circuit the winding of the relay RA to 105 deenergize the same and to cause it to retire its armatures, thus breaking this locking circuit hitherto existing through its contact 69, as described. The relay CR having been 110 retired when the switching mechanism LSW was retired, the contact 69 being once opened, as described, the relay RA cannot again be operated during this established talking connection.

The talking connection is now established 115 by the release of the relay RA, by the closure of contacts 98, which contacts being closed interconnect corresponding line conductors of each of the connected lines through a condenser KK, a connection for 120 the flow of battery current existing for each of the lines and connected to each side of this condenser, connection for the calling line existing through the winding of the calling subscriber controlled relay SR, and 125 for the called subscriber through the impedance coil 99. A common connection to the ground pole of battery for both of the lines exists through the impedance coil ZZ.

For the sake of added clearness it will be 130

explained that now the flow of talking currents will be had over a circuit extending from the substation A including the line conductors LA, now closed contacts 111 and 5 112 of the calling line relay CO, active wipers 22 and 23 of the calling line switch LSA, passive contacts 27 and 28 of the trunk circuit TK, and from thence to the line conductors LB of the called line through 10 a passive contact 7 and active wiper 2 of the line switch LSB and now closed contacts 85 to one line conductor, and through the condenser KK and normal contacts 98 of the relay RA, passive contact 9 and active wiper 4 of the called line switch LSB, 15 now closed contacts 76 of the relay SWR, and now closed contacts 86 of the relay CO to the other line conductor of the called line.

20 The subscribers now being in conversational circuit will be able to converse, talking battery being supplied for the transmitters until such time as the conversational period is ended, whereupon the calling subscriber A 25 will retire his instrument, thus opening the switch contacts 101 in the circuit of the subscriber controlled relay SR, which opening the contacts 113 in the operating circuits of the relays LSR and RL will restore 30 these relays, the relay CR having already been restored, as described. The relay LSR being operated will open the ground connection to the passive test contacts of the trunk TK hitherto existing through the 35 contact 110, and the cut-off relay CO in the circuit of these contacts will be restored to normal. Also the relay SR deenergizing will cause its contacts 154 to be opened for a definite interval preceding the subsequent 40 closure of the contacts 152, so that for a moment the circuit conductor 155 will be interrupted, it being understood that the relay RL is relatively slow releasing, and during this interval the relay CO of the 45 called line switch will be released, its winding being previously energized over a circuit including the conductor 155. Subsequent to the release of the relay CO which restores the circuits of the called line switch 50 LSB to normal, contacts 152 will again be closed replacing a connection to ground upon the conductor 155 and the passive contacts associated therewith in the different line switches through normal contacts 71 of 55 the relay CR.

The circuits have now all been restored to normal and may be used again in establishing new connections.

In passing it will be said that the common 60 relay E for a plurality of switching mechanisms, as LSW, performs the function which has been briefly referred to in this description of preventing the rotation of the switch wiper RSW when one of the switching mechanisms, LSW is exercising a control 65

over a called line switch, this time interrupting the circuit at its opened contacts 58 of the stepping magnet F of the rotary switch having the wiper RSW. This for a purpose made plain from the description. 70

It will be understood that while I have illustrated and described a specific embodiment involving specific structures for the illustrating and use of my invention, that I do not desire to be limited to the specific 75 structures illustrated and described, but am aware that numerous and extensive departures may be made without departing from the spirit of the invention.

What I claim is: 80

1. In a telephone system, the combination with a calling subscriber's line, a called subscriber's line, non-numerical trunk finding switches for the use of each of the said lines, a group of trunk circuits common to the 85 said lines, substation apparatus for the said lines, means responsive to calling line substation control to operate the calling line switch to make connection with one of the said trunk lines, a plurality of directly controlled switching mechanisms, a non-numerical switch for each of the said trunk circuits, means associated therewith to cause the said trunk circuit non-numerical switch with which the said calling line is associated 90 to operate to connect to one of the said switching mechanisms, means responsive to calling line substation control to operate the said switching mechanism to make connection with a terminal associated with a desired called line, means responsive to the said connection to cause the said non-numerical trunk finding switch of the called line to operate to connect the called line with the said trunk circuit to which the calling 95 line has been connected, and means responsive to the connection between the said trunk circuit and the said called line to dissociate the said switching mechanism from the said trunk circuit. 100

110 2. In a telephone system, the combination with a plurality of telephone lines, substations for the said lines, a main station, a single individual line switch for each of the lines at the main station, a plurality of trunk 115 circuits, means associated with each of the individual line switches to cause the same to connect its line with an idle one of the said trunk circuits, a plurality of switching mechanisms adapted to be directly controlled, 120 non-numerical interconnecting means to interconnect an idle one of the said switching mechanisms and a trunk circuit to which connection has been made by a calling line, by the operation of the calling line individual switch, a sending mechanism at the 125 said substation adapted to control the directive operation of the said switching mechanism to cause it to make connection with a terminal of a desired called line, means 130

responsive to the said connection to cause the called line switch to make connection with the same trunk circuit previously connected to by the calling line, and means responsive 5 to this last caused connection to dissociate the said switching mechanism.

3. In a telephone system, the combination with a plurality of telephone lines, substations for the said lines, a main station, an 10 individual switch for each of the said lines at the said main station, a plurality of switch wipers for each of the said line switches, a plurality of trunk circuits in a group common to the said lines, terminating contact 15 sets for circuit conductors of each trunk circuit in each line switch, a pair of the said wipers being used in extending a talking connection between a calling line and a connected trunk circuit, a pair of the said wipers 20 being used to extend a talking connection between a called line and a connected trunk circuit, at least one of the wipers of each set of wipers of a given line switch being solely used when the line is a calling line, and another 25 other of the wipers being solely used when the line is a called line, means to operate a calling line switch under substation control to make connection between a calling line and an idle trunk circuit, and means there- 30 after operative to cause the operation of a called line switch to make connection with the same trunk circuit.

4. In a telephone system, the combination with a plurality of telephone lines, substations for the lines, a main station, an individual line switch for each line at the main station, a plurality of trunk circuits, terminals for the said trunk circuits connected to contacts of each of the said line switches, 40 propelling means for each of the line switches, active switch wipers for each of the line switches, the said propelling means being adapted to move the said wipers successively over sets of contacts for each of the 45 said trunk circuits, means to cause a calling line switch to make connection with the contacts associated with a non-engaged trunk circuit, and selecting apparatus associated with the selected trunk circuit to select the 50 line switch of a called subscriber, and to cause the said line switch to be moved by its propelling means to cause its wipers to connect with the said connected trunk circuit.

5. In a telephone system, the combination 55 with a calling subscriber's line, an individual line switch therefor having wipers, means to cause the said line switch to select and to connect to a non-engaged one of a group of trunk circuits, said group of trunk circuits 60 being common to a group of individual switches, selecting apparatus thereafter operated through the said line switch and circuit conductors of the said selected trunk circuit under the control of calling subscriber 65 substation apparatus to operate the line

switch of a called subscriber's line, means operated under the control of the said selecting apparatus to alter the electrical condition of one of the contacts of the connected trunk circuit, to cause the said called line individual switch to come to rest with its wipers, engaging a set of contacts associated with the said connected trunk circuit, and means responsive to the connection between the said connected trunk circuit and the said 75 called line switch wipers, to discharge the selecting apparatus from its association with the called line switch.

6. In a telephone system, the combination with a calling subscriber's line, an individual line switch therefor having wipers, means to cause the said line switch to select and to connect to a non-engaged one of a group of trunk circuits, said group of trunk circuits being common to a group of individual switches, selecting apparatus thereafter operated through the said line switch and circuit conductors of the said selected trunk circuit under the control of calling subscriber 80 substation apparatus to operate the line 85 switch of a called subscriber's line, means operated under the control of the said selecting apparatus to alter the electrical condition of one of the contacts of the connected trunk circuit, to cause the said called line individual switch to come to rest with its wipers, engaging a set of contacts associated with the said connected trunk circuit, means responsive to the connection between the said 90 connected trunk circuit and the said called line switch wipers, to discharge the selecting apparatus from its association with the called line switch, and means to restore the said selective apparatus to its normal position to make it available for the use of other 95 calling subscribers.

7. In a telephone system, the combination with a calling telephone line, a called telephone line, a set of switch wipers including an outgoing switch wiper and sets of passive contacts for each of the lines, a stepping magnet adapted to propel the said switch wipers into successive contact with successive sets of passive switch contacts, trunk 110 circuits including circuit conductors, circuit connections from each set of contacts to circuit conductors of a given trunk circuit, one at least of said circuit conductors being an outgoing conductor for use when connection is made to a trunk circuit by a calling line, 115 and one other at least of said circuit conductors being an incoming circuit conductor for use when connection is made between the said trunk circuit and a called line, a switching relay for each of the switch wipers, a 120 circuit conductor leading to a movable contact of the said switching relay and through a normal resting contact for the said movable contact to the said outgoing switch wiper, and through a normally disconnected 125 130

contact for the said movable contact to the said incoming circuit conductor of such a trunk circuit as may be connected through the wipers of the said line switch.

5 8. In a telephone system, the combination with a first line, a second line, a plurality of trunks common to the lines, non-numerical switching means for each of the lines, a test circuit controlling each switching means, a 10 relay controlling each test circuit, and circuit connections and apparatus to cause the said switching means to select and to connect with an idle trunk when the contacts of the relay are in one operative condition, and to 15 cause the said switch to select and connect to a particular trunk when the said relay is in a different operative position.

9. In a telephone system, the combination with a plurality of lines, a plurality of link 20 circuits, a switch for each line to connect it to an idle link circuit, and means including a relay for each switch to cause the said switch to connect its associated line to a particular link circuit.

25 10. In a telephone system, the combination with a plurality of lines, a plurality of link circuits, a switch for each line to connect it to an idle link circuit, and means including a relay for each switch to cause the 30 said switch to connect its associated line to a particular link circuit to which a single one of the said switches has already been connected.

11. In a telephone system, the combination 35 with a plurality of lines, one of the said lines being a calling line, a plurality of link circuits, a switch for each line to connect it to an idle link circuit, and means including a relay for each switch to cause the 40 said switch to connect its associated line to a particular link circuit to which a calling line of the said switches has already been connected.

12. In a telephone system, the combination 45 with a plurality of lines, substations for the said lines, a plurality of link circuits common to the said lines, a single individual line switch for each line, means to cause a line switch to operate under the 50 control of calling substation apparatus to connect its associated line with an idle link circuit, and means including a relay for each line switch to cause the said line switch to operate under the control of the substation apparatus of another line to connect its associated line to a particular link circuit.

55 13. In a telephone system, the combination with a plurality of lines, one of the said lines being a calling line, a plurality of link 60 circuits, a switch for each line to connect it to an idle link circuit, means including a relay for each switch to cause the said switch to connect its associated line to a particular link circuit to which a calling line of the 65 said switches has already been connected,

and selective apparatus under the control of calling line apparatus to select and operate the relay of a desired called line.

14. In a telephone system, the combination with a plurality of lines, substations for 70 the said lines, a plurality of link circuits common to the said lines, a single individual line switch for each line, means to cause a line switch to operate under the control of calling substation apparatus to connect 75 its associated line with an idle link circuit, means including a relay for each line switch to cause the said line switch to operate under the control of the substation apparatus of another line to connect its associated 80 line to a particular link circuit, and selective apparatus under the control of calling line apparatus to select and operate the relay of a desired called line.

15. In a telephone system, the combination 85 with a plurality of lines, one of the said lines being a calling line, a plurality of link circuits, a switch for each line to connect it to an idle link circuit, a relay for each switch to cause the said switch to connect 90 its associated line to a particular link circuit to which a calling line of the said switches has already been connected, selective apparatus under the control of calling line apparatus to select and operate the relay of a desired called line, and means responsive thereto to cause its associated switch to operate to connect a calling line and called line to a previous calling-line-switch-selected trunk circuit.

16. In a telephone system, the combination with a plurality of lines, substations for 100 the said lines, a plurality of link circuits common to the said lines, a single individual line switch for each line, means 105 to cause a line switch to operate under the control of calling substation apparatus to connect its associated line with an idle link circuit, a relay for each line switch to cause the said line switch to operate under the control of the substation apparatus of another line to connect its associated line to a particular link circuit, selective apparatus under the control of calling line apparatus to select and operate the relay of 110 a desired called line, and means responsive thereto to cause its associated switch to operate to connect a calling line and called line to a previous calling-line-switch-selected trunk circuit.

17. In a telephone system, the combination with a plurality of lines, a calling one of the said lines, a line switch for each line, a set of wipers for each switch, comprising calling and called wipers, a plurality of 115 trunk circuits, a set of contacts for each trunk circuit on each switch in the path of travel of the set of wipers thereof, each set of trunk circuit contacts comprising incoming and outgoing terminals for its associated 120 125 130 135 140 145 150 155 160 165 170 175 180

trunk circuit, calling line apparatus to control the operation of its switch to connect to an idle trunk circuit through calling switch wipers and incoming trunk circuit 5 contact terminals, and selective apparatus operated under the control of the calling line apparatus to cause a selected called line switch to connect to the calling line switch selected trunk circuit through "called" 10 wipers of the called line switch and outgoing terminal contacts of the said trunk circuit.

18. In a telephone system, the combination with a plurality of lines, a calling one of the 15 said lines, a line switch for each line, a set of wipers for each switch, comprising calling and called wipers, a plurality of trunk circuits, a set of contacts for each trunk circuit on each switch in the path of travel of 20 the set of wipers thereof, each set of trunk circuit contacts comprising incoming and outgoing terminals for its associated trunk circuit, calling line apparatus to control the operation of its switch to connect to an idle 25 trunk circuit through calling switch wipers and incoming trunk circuit contact terminals, selective apparatus operated under the control of the calling line apparatus to cause a selected called line switch to connect to 30 the calling line selected trunk circuit through "called" wipers of the called line switch and outgoing terminal contacts of the said trunk circuit, and busy test means to prevent the operation of the said called line switch.

35 19. In a telephone system, the combination with a plurality of lines, a calling one of the said lines, a single individual line switch for each line, a set of wipers for each switch, comprising calling and called wipers, a plurality 40 of trunk circuits, a set of contacts for each trunk circuit on each switch in the path of travel of the set of wipers thereof, each set of trunk circuit contacts comprising incoming and outgoing terminals for its associated trunk circuit, calling line apparatus to control the operation of its switch to connect to an idle trunk circuit through calling switch wipers and incoming trunk circuit contact terminals, and selective apparatus 45 operated under the control of the calling line apparatus to cause a selected called line switch to connect to the calling line switch selected trunk circuit through "called" wipers of the called line switch and outgoing 50 terminal contacts of the said trunk circuit.

55 20. In a telephone system, the combination with a plurality of lines, a calling one of the said lines, a single individual line switch for each line, a set of wipers for each switch, comprising calling and called wipers, a plurality 60 of trunk circuits, a set of contacts for each trunk circuit on each switch in the path of travel of the set of wipers thereof, each set of trunk circuit contacts 65 comprising incoming and outgoing ter-

minals for its associated trunk circuit, calling line apparatus to control the operation of its switch to connect to an idle trunk circuit through calling switch wipers and incoming trunk circuit contact terminals, selective apparatus operated under the control of the calling line apparatus to cause a selected called line switch to connect to the calling line selected trunk circuit through "called" wipers of the called line switch and 70 outgoing terminal contacts of the said trunk circuit and busy test means to prevent the operation of the said called line switch.

21. In a telephone system, the combination with a plurality of lines, a calling one of the 80 said lines, a line switch for each line, a set of wipers for each switch, comprising calling and called wipers, a plurality of trunk circuits, a set of contacts for each trunk circuit on each switch in the path of travel of the 85 set of wipers thereof, each set of trunk circuit contacts comprising incoming and outgoing terminals for its associated trunk circuit, calling line apparatus to control the operation of its switch to connect to an idle 90 trunk circuit through calling switch wipers and incoming trunk circuit contact terminals, selective apparatus operated under the control of the calling line apparatus to cause a selected called line switch to connect to the calling line selected trunk circuit through "called" wipers of the called line switch and outgoing terminal contacts of the said trunk circuit, busy test means to prevent the operation of the said called line switch, and 95 an automatic ringing mechanism responsive to the selection of the called line switch to connect a ringing generator to the outgoing terminals of the said trunk circuit.

22. In a telephone system, the combination with a plurality of lines, substations for the said lines, a plurality of link circuits common to the said lines, a single individual line switch for each line, means to cause a line switch to operate under the control of calling 100 substation apparatus to connect its associated line with an idle link circuit, and means including a relay for each line switch to cause the said line switch to operate under the control of the substation apparatus of another line to connect its associated line to a particular link circuit to which a single one of the said switches has already been connected.

23. In a telephone system, the combination with a plurality of lines, substations for the said lines, a plurality of link circuits common to the said lines, a single individual line switch for each line, means to cause a line switch to operate under the control of calling 105 substation apparatus to connect its associated line with an idle link circuit, means including a relay for each line switch to cause the said line switch to operate under the control of the substation apparatus of 110 another line to connect its associated line to a particular link circuit to which a single one of the said switches has already been connected.

another line to connect its associated line to a particular link circuit to which a single one of said switches has already been connected, and selective switching mechanism associated with the link circuit to which a calling line is connected to select the relay of a desired called line switch.

24. In a telephone system, the combination with a plurality of lines, a calling one of the said lines, a single individual line switch for each line, a set of wipers for each switch, comprising calling and called wipers, a plurality of trunk circuits, a set of contacts for each trunk circuit in each switch in the path of travel of the set of wipers thereof, each set of trunk circuit contacts comprising incoming and outgoing terminals for its associated trunk circuit, calling line apparatus to control the operation of its switch to connect to an idle trunk circuit through calling switch wipers and incoming trunk circuit contact terminals, selective apparatus operated under the control of the calling line apparatus to cause a selected called line switch to connect to the calling line selected trunk circuit through "called" wipers of the called line switch and outgoing terminal contacts of the said trunk circuit, busy test means to prevent the operation of the said called line switch, and automatic ringing mechanism responsive to the selection of the called line switch to connect a ringing generator to outgoing terminals of the said trunk circuit.

25. In a telephone system, the combination with a plurality of lines, a calling one of the said lines, a line switch for each line, a set of wipers for each switch, comprising calling and called wipers, a plurality of trunk circuits, a set of contacts for each trunk circuit on each switch in the path of travel of the set of wipers thereof, each set of trunk circuit contacts comprising incoming and outgoing terminals of the associated trunk circuit, calling line apparatus to control the operation of its switch to connect to an idle trunk circuit through calling switch wipers and incoming trunk circuit contact terminals, selective apparatus operated under the control of the calling line apparatus to cause a selected called line switch to connect to the calling line selected trunk circuit through "called" wipers of the called line switch and outgoing terminal contacts of the said trunk circuit, busy test means to prevent the operation of the said called line switch, and automatic ringing mechanism responsive to the selection of the called line switch to connect a ringing generator to outgoing terminals of the said trunk circuit.

26. In a telephone system, the combination with a plurality of lines, a calling one

of the said lines, a line switch for each line, a set of wipers for each switch, comprising calling and called wipers, a plurality of trunk circuits, a set of contacts for each trunk circuit on each switch in the path of travel of the set of wipers thereof, each set of trunk circuit contacts comprising incoming and outgoing terminals for its associated trunk circuit, calling line apparatus to control the operation of its switch to connect to an idle trunk circuit through calling switch wipers and incoming trunk circuit contact terminals, selective apparatus operated under the control of the calling line apparatus to cause a selected called line switch to connect to the calling line selected trunk circuit through "called" wipers of the called line switch and outgoing terminal contacts of the said trunk circuit, busy test means to prevent the operation of the said called line switch, an automatic ringing mechanism responsive to the selection of the called line switch to connect a ringing generator to the outgoing terminals of the said trunk circuit, a substation for each of the lines, and means responsive to the connection of the substation of the called line to its line conductors to disable the said ringing generator connecting circuit.

27. In a telephone system, a calling line, a called line, a line switch for the individual use of each line, each line switch being provided with contacts and wipers normally engaging certain of said contacts, link circuits terminating in said contacts, means for operating the individual switch of a calling line to seize a link circuit, means controlled over the calling line for causing the individual line switch of the called line to seize the link circuit with which the calling line switch is in engagement.

28. In a telephone system, a calling line, a called line, a line switch for the individual use of each line, each line switch being provided with contacts and wipers arranged to remain in engagement with the contacts last used, link circuits terminating in said contacts, means for operating the individual switch of a calling line to seize a link circuit, means controlled over the calling line for causing the individual line switch of the called line to seize the link circuit with which the calling line switch is in engagement.

29. In a telephone system, a calling line, a called line, a line switch for the individual use of each line, each line switch being provided with contacts and wipers arranged to remain in engagement with the contacts last used, said switch being released by merely electrically disconnecting its wipers from its line circuit, link circuits terminating in said contacts, means for operating the individual switch of a calling line to seize a link circuit, means controlled over the calling line for causing the individual line

switch of the called line to seize the link circuit with which the calling line switch is in engagement.

30. In a telephone system, a group of telephone lines, a switch for each line having wipers, link circuits accessible to said switches, means for causing the line switches of a calling line and a called line to seize opposite ends of a link circuit in completing a conversational circuit, and means for completing one connection at a time in said group.

31. In a telephone system, a group of telephone lines, link circuits, a switch having contacts and wipers individual to each line, each switch being arranged to hold its wipers in engagement with the contacts last used, means for causing the line switches of a calling and a called line to seize opposite ends of a link circuit in completing a conversational circuit, and means for completing one connection at a time in said group.

32. In a telephone system, an individual line switch for each line having contacts,

trunk conductors terminating at each end in contacts of said line switches, said conductors being continuous between said contacts, a source of transmitter current bridged across said trunks, and means for causing the calling and called line switches to seize a trunk in completing a telephone connection.

33. In a telephone system, a group of telephone lines, a plurality of rotary step by step non-numerical switches, each switch having contacts and wipers certain of which are individual to each telephone line, each switch being arranged to hold its wipers in the position last used, a plurality of link circuits, means for causing the switch wipers of a calling and a called telephone line to set up and hold a telephone connection through a link circuit and means for completing the setting of one connection at a time in said group.

In witness whereof, I hereunto subscribe my name this 2nd day of January, A. D. 1919.

FRANK M. SLOUGH.
